[57] ABSTRACT

A high intensity metal vapor electric discharge lamp having self-heating main electrodes at opposite ends and a starter electrode at one end. A cermet igniter comprising a sintered mixture of metal and refractory or emissive metal oxide is attached to and spaced close to the main electrode at the end having the starter electrode. The igniter operates as much as 1,000°C. cooler than the main electrode and retains its emission material throughout life. A glow or arc initiated on it readily transfers to the main electrode. It serves to reduce the starting voltage or prevent rise in starting voltage in seasoned lamps.

HIGH INTENSITY LAMP WITH CERMET IGNITER

BACKGROUND OF THE INVENTION

The invention relates to metal vapor arc lamps using an arc discharge in metal or metal halide vapors to produce light, and is particularly concerned with the starting of such lamps.

High pressure metal vapor lamps such as mercury or metal halide lamps generally have self-heating main electrodes at opposite ends and are usually provided with an auxiliary starting electrode. It may take the form of a starter wire spaced close to one of the main electrodes. The latter is usually negative, or cathode, at the a.c. phase moment when ignition occurs, so that it is convenient to speak of this main electrode adjacent to the auxiliary electrode as "cathode," and of the other more distant main electrode as "anode." After closing the circuit, when the starter voltage becomes sufficiently positive a glow discharge appears between starter and cathode. This glow discharge quickly transfers to the anode from the starter, and subsequently is converted into an arc, such completing the ignition process.

The main electrodes comprise a base metal body bearing emission material, the form commonly used being a close wound tungsten coil bearing low work function emission mix in the interstices between turns. Presence of the emission material tends to facilitate ignition of the glow discharge or Paschen breakdown and also transition of the glow into an arc. However, operation of the lamp with repeated starts tends to remove the emission material by processes such as ion bombardment and simple flaking due to thermal expansion or distortion. Concomitantly, it is observed that some lamps become "hard starters" as life progresses.

SUMMARY OF THE INVENTION

We have reasoned that the development of hard starting in discharge lamps and particularly in metal halide lamps may result from loss of emission material from electrodes in service. The potential hazard is greater under low temperature conditions where the available voltage has a relatively small margin over that required for starting. The benefit of emission mix, namely low electrode voltage drop, occurring during normal arc burning is not possible without some dispensing of the emission material to the cathode terminus. Some deletion is therefore necessary, even though the rate may be low, and it can be accelerated by wandering of the cathode terminus or by split spot mode of burning.

In accordance with our invention, the development of hard starting with life is prevented by assuring that there is emission mix available to provide normal starting throughout life. This is achieved by providing an igniter having a well-bonded supply of emission mix in a region out of range of the normal wandering of the arc terminus and maintained at a temperature several hundred degrees Centigrade lower than the front end of the main electrode.

In a preferred embodiment of the invention, a ceramic-metal or cermet igniter comprising a sintered mixture of metal and metal oxide on a conductor is attached to the main electrode at the end of the lamp having the auxiliary electrode. The metal oxide may be refractory, or emissive, or preferably refractory and

emissive. A desirable arrangement is to locate the igniter in the space between the main electrode and the auxiliary electrode. A glow or arc initiated at the cermet igniter can readily transfer to the cathode. The end 5 of the cermet igniter is placed back from the tip or face of the cathode so that the arc, which prefers a short length, will quickly transfer to the cathode. The cermet igniter operates at least 1,000°C. cooler than the main electrode and retains its emission material throughout life. Thus it serves to reduce the starting voltage or prevent rise in starting voltage in seasoned lamps.

DESCRIPTION OF DRAWING

In the drawing:

FIG. 1 shows in side view a metal halide lamp embodying the invention.

FIG. 2 is an enlarged sectioned view of the "cathode" electrode provided with cermet igniter.

DESCRIPTION OF PREFERRED EMBODIMENT

Referring to FIG. 1 of the drawing, a mercury metal halide vapor arc lamp 1 in which the invention is embodied comprises an outer vitreous envelope or jacket 2 of ellipsoidal form having a neck portion 3. The neck is closed by a re-entrant stem 4 having a press 5 through which extend stiff inleads 6,7. These inleads are connected at their outer ends to the contacts of the usual screw-type base 8, namely the threaded shell 9 and the insulated center contact 10.

The inner arc tube 12 made of quartz or fused silica has therein at opposite ends a pair of main arcing electrodes, 13 at the base end and 14 at the dome end, plus an auxiliary starting electrode 15 at the base end. The electrodes are supported on inleads which include intermediate thin molybdenum foil sections 16 hermetically sealed to the flattened ends 17, 18 of the arc tube, commonly referred to as full diameter pinch seals. The main electrodes 13, 14 each comprise a double layer tungsten wire helix 19 (best seen in FIG. 2) wrapped around a tungsten core wire 20. The main electrodes are activated by thorium oxide which coats the turns and fills the interstices within the helix.

The arc tube is supported within the outer jacket by 45 a divided or two-part mount. The lower mount section comprises U-shaped support rod 21 welded to inlead 6 and having metal straps 22 extending across its ends to clamp pinch seal 17. The upper mount section comprises inverted U-shaped support rod 23 to which is attached a springy collar 24 engaging a re-entrant dimple 25 in the dome end of the outer envelope, and which has straps 26 extending across its ends and clamping pinch seal 18. The right angle braces 27 connected to support rods 21 and 23 engage blind notches 28 in the ends of pinch seals 17, 18 to stiffen the assembly.

Main electrode 13 is connected to inlead 6 through strap 29 and the lower support rod, while main electrode 14 is connected to inlead 7 through curving wire 31. Starting electrode 15 is connected to inlead 7 through a current limiting resistor 32 which may have a value for instance of 40,000 ohms. A thermal switch consisting of a U-shaped bimetal 33 is welded at one end to the inlead of main electrode 13 with its free end disposed to engage the inlead of starting electrode 15 as the lamp warms up. The auxiliary electrode is thereby connected to the adjacent main electrode during operation of the lamp whereby to prevent harmful

electrolytic effects in accordance with the teachings of U.S. Pat. No. 3,226,597 to Green.

The arc tube contains an inert rare gas such as argon at a low pressure, for instance 25 torr, to facilitate starting and warm-up, and a fill of metal or metal halide. By way of example the arc tube may contain a quantity of mercury which is substantially totally vaporized and exerts a partial pressure in the range of 1 to 15 atmospheres during operation. Additionally there may be contained a metal halide such as sodium iodide in excess of the quantity vaporized at the operating temperature, plus smaller amounts of other metal halides such as thallium and indium iodides, or scandium iodide.

In accordance with our invention, the availability of emission mix for normal starting is assured by providing a well-bonded supply of it in a region out of range of the normal wandering of the arc terminus. In the illustrated embodiment best seen in FIG. 2, such supply takes the form of a ceramic or cermet igniter 35. The igniter comprises a sintered mixture of refractory metal and emissive or refractory metal oxide powders as a coating 36 on a refractory metal wire 37 which is welded to core wire 20 of main electrode 13 below or to the rear of helix 19. The preferred mixture for a metal halide containing lamp is tungsten powder and thoria, each 50 percent by weight. The mixture, in a flexible sleeve of polyvinyl chloride, is pressed at 40,000 pounds per square inch around an 18 mil diameter tungsten wire. The sleeve is dissolved away and the green compact is then fired in vacuo for an hour at temperatures of 1,750° to 2,000°C. After firing, the thickness of the cermet coating 36 around wire 37 averaged approximately 6 mils. Other mixtures which have been used include tungsten and alkaline earth oxides; tungsten, thoria, and rare earth oxides; and tungsten, tungsten carbide, and thoria.

The tip or upper end of the igniter 35 is preferably placed back from the tip or front face of electrode 13 in order that the arc, which prefers a short path, will quickly transfer to the "cathode," that is, to electrode 13. The cap shape of the cermet coating 36 is not critical and wire support 37 may project through the coating without harm.

The tip of auxiliary starter electrode 15 is shown in dash lines in FIG. 2 to indicate its location relative to the igniter. Ignition starts as a glow discharge between starter wire 15 and igniter 35. The discharge transfers without delay from starter to "anode" 14 and from igniter to contiguous "cathode" 13 and develops into an arc. Operating temperature of the cermet igniter, about 900°C., is at least 1,000° Centigrade below that of the upper coil region of the main electrode, so the igniter does not dispense emission mix as does the electrode. Also sputtering due to spot motion, routine on the main electrode, is absent from the igniter.

In lamps provided with igniters according to the invention, moderate reduction in voltage required to start at room temperature was observed in lamps seasoned less than 1 hour; the reduction became more substantial, about 7 percent, after more starts and longer seasoning. This is shown in Table 1 below for lamps containing mercury and metal iodides. The term "fast cycle" denotes a start including 2 seconds of burning followed by 28 seconds off for accelerated seasoning.

TABLE 1

	Average RMS Starting Voltages			
	At 50°F.		At -20°F.	
	Control Lamps	With Igniters	Control Lamps	With Igniters
5				
After 1 hour or less of seasoning	237	221	237	230
After 20 starts and 100 hours seasoning	220	207	247	233
After 220 starts and 300 hours seasoning	220	203	247	237
After 220 starts and 300 hours seasoning and 8000 "fast cycles"	203	190	233	217

There is also an appreciable reduction, up to 6%, at lower temperatures (-20°F.) where starting is often problematical.

What we claim as new and desire to secure by Letters Patent of the United States is:

1. A high intensity metal vapor lamp comprising: a vitreous envelope containing metal vapor and having a pair of thermionic self-heating arc-supporting main electrodes sealed therein at opposite ends and a starter electrode at one end; and an igniter connected to the main electrode at said one end, said igniter comprising a sintered mixture of metal and metal oxide on a conductor, said igniter being spaced close to the main electrode to which it is connected whereby it operates at a lower temperature without appreciable loss of metal oxide and a discharge initiated on it readily transfers to said main electrode.
2. A lamp as in claim 1 wherein the metal oxide in said mixture is refractory or emissive oxide.
3. A lamp as in claim 1 wherein said igniter comprises a sintered mixture of tungsten powder and refractory emissive metal oxide on a tungsten conductor.
4. A lamp as in claim 1 wherein said igniter comprises a sintered mixture of tungsten powder and thorium oxide on a tungsten conductor.
5. A high intensity metal vapor lamp comprising: a vitreous envelope containing an inert starting gas, mercury and metal halide, a pair of thermionic self-heating arc-supporting main electrodes sealed into opposite ends of said envelope and a starter electrode at one end, each of said main electrodes comprising a winding of tungsten wire on a tungsten core activated by emissive metal oxide thereon, and an igniter connected to the main electrode at said one end, said igniter comprising a sintered mixture of tungsten powder and emissive metal oxide powder on a tungsten conductor attached for the tungsten core of said main electrode to the rear of the winding of tungsten wire, said igniter being spaced close to said main electrode to which it is connected, whereby it operates at a lower temperature without appreciable loss of emissive metal oxide and a discharge initiated on it readily transfers to said main electrode.
6. A lamp as in claim 5 wherein said igniter operates at a temperature at least several hundred degrees Centigrade lower than the front end of the main electrode.

7. A lamp as in claim 5 wherein the emissive metal oxide in said sintered mixture is thorium oxide.

8. A lamp as in claim 5 wherein said igniter is located between said starter electrode and the main electrode to which it is connected and projects forward less than said main electrode.
